UNITED STATES PATENT OFFICE.

BERTHA TROUTT, OF ROSEMONT, PENNSYLVANIA.

BATHING-SHOE.

1,226,720.

Specification of Letters Patent.

Patented June 5, 1917.

Application filed February 13, 1917. Serial No. 146,332.

To all whom it may concern:

Be it known that I, BERTHA TROUTT, a subject of the King of England, but now residing at Rosemont, in the county of Montgomery and State of Pennsylvania, have invented certain new and useful Improvements in Bathing-Shoes, of which the following is a specification.

My invention has relation to a bathing shoe provided with a sole adapted when becoming worn to be readily removed so as to be replaced by another laced to a perforated strip made a permanent part of the upper of the shoe; and in such connection my invention relates to the particular arrangement of the perforated strip bounding the bottom of the upper as a permanent part of the same together with a perforated sole laced to the strip with a lacing cord so as to alternately appear in oblong exposed portions around the sole to thereby securely hold the sole to the said strip, for use.

The nature, scope and characteristic features of my invention will be more fully understood from the following description taken in connection with the accompanying drawings forming part hereof, in which—

Figure 1, is an underneath plan view of the bathing shoe, embodying features of my said invention.

Fig. 2, is a similar view with the sole partially removed to show the perforated strip as part of the upper of the shoe.

Fig. 3, is a perspective view of the top of the shoe, showing the arrangement thereof, provided with a readily removable bottom laced sole.

Referring to the drawings *a*, is the upper, provided with lacings *a*¹ and *a*², for strapping the shoe to the lower part of the limb against removal.

The bottom of the upper *a*, is bounded with a perforated rubber, leather or other

tough material strip *b*, sewed or otherwise permanently made a part of the upper *a*, and extending slightly beyond the contour of the upper in form or use so that the series of perforations *b*¹, provided therein will be readily accessible.

The sole *c*, for the shoe may be of rubber, leather or other tough material with peripheral perforations at suitable distances apart provided therein for knitting or entering a lacing cord or string *d*, therethrough and the perforations *b*¹, of the strip *b*, so as to provide alternate oblong lacings on the bottom of the sole throughout the same, as clearly shown in Fig. 1, whereby the sole when it becomes worn may be readily removed and replaced by another, without affecting the upper *a*, of the shoe, for again being used.

Having thus described the nature and objects of my invention what I claim as new and desire to secure by Letters Patent is:—

A bathing shoe having the bottom of the upper secured to a strip or welt by a single line of stitching adjacent to the inner periphery of the said strip or welt and the latter projecting beyond the outline of said upper with a row of perforations located along the outer edge beyond the contour of the said upper, whereby the said perforations are easily accessible, and a sole removably attached to said strip or welt by a single lacing cord through the perforations of said strip or welt for holding said sole to said shoe.

In witness whereof, I have hereunto set my signature in the presence of two subscribing witnesses.

BERTHA TROUTT.
